Albert T. Hull

By his Attorney,
Rowland Cox

UNITED STATES PATENT OFFICE.

ALBERT T. HULL, OF NEW YORK, N. Y., ASSIGNOR TO EDWARD D. FISHER,
OF SAME PLACE.

HOD-ELEVATOR.

SPECIFICATION forming part of Letters Patent No. 286,009, dated October 2, 1883.

Application filed February 12, 1883. (No model.)

To all whom it may concern:

Be it known that I, ALBERT T. HULL, a citizen of the United States, residing at New York, in the county of New York and State of New York, have invented certain new and useful Improvements in Hod-Elevators; and I do hereby declare the following to be a full, clear, and exact description of the invention, such as will enable others skilled in the art to which it appertains to make and use the same.

The invention relates to an improvement in hod-elevators; and it consists in the novel construction and arrangement of the parts hereinafter described, and particularly pointed out in the claims.

Referring to the accompanying drawings, Figure 1 is a side view of the endless elevator-chain mounted upon its carrying-wheels, and illustrating the mechanism for applying power, situated at the upper end of the chain. Fig. 2 is an enlarged plan view of a detached portion of the endless chain supporting a hod. Fig. 3 is an edge view of the elements illustrated in Fig. 2. Fig. 4 is a view of the hod, looking at its open end. Fig. 5 is a detached perspective view of the yoke adapted to receive the hod and to suspend it on the endless carrying-chain. Fig. 6 is a detached perspective view of one of the tie-rods connecting the two sides of the endless chain. Fig. 7 is an end view of the frame supporting the mechanism by which power is applied to operate the endless chain, the gear-wheels in this view being indicated by dotted lines.

A B denote the two sides of the endless chain, and C the rods connecting the same. The endless chain passes over the wheels *a b* and under the wheels *c d*, the wheels *c d* being mounted upon an axle, *e*, which is journaled at *f* and located at the lower part of the building in which the apparatus is employed. The wheels *a b* are mounted between the sides of the frame *D* upon an axle, *E*, the said frame being situated at the upper part of the building. Upon the outer end of the axle *E* is secured the gear-wheel *F*, below and meshing with which is an intermediate gear-wheel, *G*, which is mounted upon an axle, *g*, projected from the plate *h*. The plate *h* is preferably embedded in the side of the frame *D*, as indicated in dotted lines in Fig. 1 and in full lines

in Fig. 7, and is employed merely to sustain the intermediate gear-wheel, *G*. Below the wheels *a b* the sides of the frame *D* are connected by a shaft, *H*, having upon either extremity the crank *I*, and being provided with the pinion *J*, which meshes with the intermediate gear-wheel, *G*. The shaft *H* is also supplied with the ratchet-wheel *i*, which is engaged by the pawl *j*. The purpose of the pawl *j* and ratchet *i* is to prevent the shaft *H* from being turned in the wrong direction by the weight of the load on the chain when the attendant's hand is removed from the crank. It will appear plain that by turning the cranks *I*, or either of them, motion will be communicated from the pinion *J*, through the intermediate gear-wheel, *G*, to the gear-wheel *F*, and thence to the shaft *E* and wheels *a b*. The motion of the wheels *a b* causes the usual travel of the endless belt or chain over the wheels, carrying it toward the top of the building.

The endless chain consists of the open links *m* and closed links *n*, the links being connected at their meeting ends by bolts, rivets, or other suitable means. The inner half of each open link *m* has formed upon it the pocket *t*, the pocket on each alternate link opening upward, the mouth of the pocket on the other links being turned downward. I do not confine myself to this arrangement of the pockets *t*, nor to the forming of them on the open links, although I prefer so to use them.

The pockets *t* are of suitable size to snugly receive the projecting ends *u* of the hod-yoke *w*, in the manner indicated in Figs. 2 and 3, and permit their ready removal when desired. The yoke *w* is a malleable-iron frame, of dimensions which adapt it to saddle the sides of the bowl *x* of the hod, and has a socket formed in its lower end to receive the upper end of the handle *y*, as shown in dotted lines in Fig. 2. The projecting ends *u* of the yoke *w* form convenient means for suspending the hod on the chain, and the yoke at the same time serves to strengthen the sides of the bowl *x* and affords a means of attachment for the handle *y*. The bowl *x* of the hod is provided at its open end with the brace or cross-bar *z*, which extends from one side of the hod to the other, and has its bent ends *a* secured by nails or otherwise. The brace *z* fulfills a twofold

purpose: It strengthens the hod and effectually prevents the brick from falling therefrom when the apparatus is in use.

The particular form of the rods C is illustrated in Fig. 6. They consist of the parts b', having bent ends c' c', which ends, when the rods are in use, are inserted in the space formed between the sides of the open links m, and secured therein by a bolt passing through the links m and the said ends c' c' at each side of the chain. The rods C are secured at suitable intervals on the endless chain, and are employed for connecting the sides A B and as a rest for the handle of the hod. Any suitable number of rods C may be employed, according to the length of the chain and other circumstances.

When the apparatus is in use, power is applied to set the chain in motion, and the hods, 20 after being filled, are inserted endwise between the sides of same until the projecting ends u of the yoke w reach the upwardly turned pockets t, which will then sustain the hod until it is removed from the chain at the 25 upper part of the building by an attendant. While the chain is passing over the pulleys a b the pockets t which were employed for sustaining the full hods will turn down, and the pockets t which were previously down will 30 now have their mouths turned upward, and in this position may be utilized for carrying the empty hods to the lower part of the building on the reverse side of the chain.

It will be obvious that by the peculiar construction of the frame D a very durable and compact means for supporting the power mechanism is provided, and that by the employment of the intermediate gear-wheel, G, I am enabled to leave the crank-shaft in a convenient position to be handled by the operator, and at the same time have the wheels a b properly elevated above the base upon which the frame D rests, to permit the bowl of the hod to reach an elevation corresponding, about, with that 45 of a man's shoulder before it is necessary to remove it from the chain. The removal of the hod is facilitated also by the manner in which it is sustained on the chain, a very short movement being sufficient to relieve the 50 extended portions of the yoke from the pockets t. Unless the hod is removed from the pocket at the proper time, it will of course be carried to the top of the wheels a b and dump the brick down through the building; 55 hence it is quite essential, especially where steam-power is employed to operate the endless chain, to adopt some means which will permit the detachment of the hods with certainty and rapidity, and which at the same 60 time will properly sustain the hods in their ascent. Other advantages are derived from the employment of the particular form of chain shown and described, which do not require specific mention. One, however, is that the 65 sides A B of the chain need only be separated the width of the hod, and will as a con-

sequence occupy but a narrow space in the building.

By arranging the power mechanism at the upper part of the building, advantages are 70 gained of a very important character. When thus arranged, the motive power can be arrested at any time to suit the purposes of the workmen in the upper portions of the building, and in case the attendant fails to remove 75 the hod of material at the proper time it will be apparent to the person operating the crank, and the movement can then be stopped, thereby avoiding the breakage of the apparatus and the danger arising from falling brick which 80 would otherwise ensue.

What I claim as my invention, and desire to secure by Letters Patent, is—

1. The means for communicating motion to the belt or chain pulleys of a hod-elevator, 85 which consists of the gear-wheels F J and intermediate wheel, G, the wheel J being mounted on the axle to which power is applied and the wheel F upon the axle carrying the said pulleys, substantially as and for the purpose 90 set forth.

2. The frame D, formed of the sides connected by the shafts E H, in combination with the wheels a b, the gear-wheels F G J, and an endless hod-carrying chain or belt, substantially as set forth.

3. The chain consisting of the sides A B, composed of open and closed links m n, and connected by the rods C, having ends c c, as described.

4. The hod having across its open end the safety-brace z, substantially as set forth.

5. In combination with an endless hod-elevating belt or chain, the hod supplied with the yoke w at about its vertical center, the yoke having projecting ends u, and a socket to receive the handle y, substantially as set forth.

6. The chain consisting of the open and closed links, constituting sides A B, provided 110 with pockets t, and connected by rods C, in combination with the hods having at about their vertical center projections u, adapted to enter the pockets, the arrangement of the chain being such as to permit the insertion of the hod between the sides thereof, substantially as specified.

7. The means for communicating motion to the belt or chain pulleys of a hod-elevator at the upper part of the building, which consists 115 of the crank-shaft, pawl and ratchet, gear-wheels F J, intermediate gear-wheel, G, the wheel F being mounted on the shaft carrying said chain-pulleys, substantially as set forth.

In testimony whereof I affix my signature in 120 presence of two witnesses.

ALBERT T. HULL.
